UNITED STATES PATENT OFFICE.

WILLIAM H. ROSE, OF JERSEY CITY, NEW JERSEY.

WINDSHIELD.

Application filed April 3, 1926. Serial No. 99,464.

My invention relates to wind shields and refers particularly to inclinable wind shields capable of insertion within, and removable from, window frames.

5 The many advantages incident to the inclined wind shield which will upwardly direct the air entering beneath a raised lower window sash have led to their general adoption as a means of ventilation.

10 As wind shields constructed for particular windows are expensive in production and are limited to their employment with the particular windows for which they are made, telescopic windshields are generally employed.

15 Inclined wind shields must be connected by some side means with the window frame in order to allow of their retention in their inclined position, and hence, means must be employed for the fastening of these side members to the window frame.

The usual method employed with wooden window frames is to nail, or screw, the side member to the frame, but this has the great 25 disadvantage of permanently marring the window frame, and the removal of the screen device uncovers the holes thus made in the frame.

30 The increased use of steel and other metallic window frame has presented greater difficulties in the attachment of wind shields. In order to attach a wind shield to a window frame of this character by means of nails or screws, it is necessary to punch, or bore, holes through the steel, or metal frame, and as this is practically impossible by an 35 inexperienced person, and as it requires special tools to accomplish it, considerable expense and inconvenience is experienced.

40 Further, the removal of the wind shield exposes unsightly holes in the window frame.

I have overcome all of the above, and other, objectionable features incident to wind shields and the device of my invention presents a wind shield capable of easy attachment to window frames, whether they be of wood or metal, without the use of nails, screws or similar penetrating devices and without injuring or marring the window frame.

45 I have found that a strip of pliable adhesive material can be attached to a window frame, whether of wood or metal, with such tenacity that it will act as a holding or retaining means for the side shields of an inclined wind shield, or that the adhesive ma-

terial may be carried by the side shields themselves for the same purpose.

It is evident that an attaching means of this character has many advantages. It may 50 be attached to the window frame by simply pressing it thereon. It does not mar the frame. It can be easily removed and as easily replaced. It presents an attractive appearance when in use and is not objectionable when the wind shield is removed. It can be easily attached to, and detached from, the wind shield. These and other advantages will be evident upon a consideration of my device.

70 The accompanying drawings illustrate modified forms of the device of my invention and will suggest other modifications inclusive within my invention.

75 In the accompanying drawings illustrating modified forms of the device of my invention, similar parts are designated by similar numerals.

Figure 1 is a front view of one form of my device in operative position.

80 Figure 2 is an enlarged cross-section through the line 2—2 of Figure 1.

Figure 3 is a cross-section through the line 3—3 of Figure 1.

85 Figure 4 is an elevational view of the side shield of Figure 1.

Figure 5 is a cross-section through the line 5—5 of Figure 4.

90 Figure 6 is an elevational view of the adhesive side of my window frame strip.

Figure 7 is an elevational view of the fastening side of my window frame strip.

95 Figure 8 is a cross-section of a modified form of my window frame strip.

Figure 9 is a cross-section of a modified form of my window frame strip.

100 Figure 10 is a broken perspective view of a modified form of my device in which the adhesive material is carried by the side shields.

The particular form of the device of my invention shown in the accompanying drawings comprises two telescopic wind shield members, one having the frame 10, 11, 12, 13 and the other having the frame 14, 15, 16, 17. The frames carry the glass panes 18 and 19, the glass being retained therein, as indicated in Figure 2, by the strip 20. The outer edge of the frame 13 is turned inwardly at 27 upon itself to form a binding and retaining means for the side shield 21.

105 A similar arrangement of parts exists

relative to the frame member 15 of the other telescopic wind shield member and such corresponding parts are indicated by prime numerals.

5 The side shield 21 is of some pliable material, as cloth, leather, etc. and is somewhat triangular in shape as shown in Figure 4. Along the edge 22 of the side shield 21 are a number of female clasp members 23, 23'. A 10 piece of metal 24 is turned over the edges 25 of the shield to maintain it in extended position. The edge 26 is held within the turned edge 27 of the frame 13.

Another element of the device of my invention comprises a strip of pliable material 28, carrying upon one face thereof a number of male clasp members 29, 29' capable of entering the female clasp member 23, 23'. Attached to the other face of the strip 28 is a 15 strip of material 30, the exposed face of which is adhesive, and having a series of openings 31, 31' through which the reverse, or fastened, end of the male members 29, 29' may pass.

20 The adhesive material 37 may be applied directly to the face of the strip 28 as shown in Figure 8, or an adhesive material 37 may be attached by adhesive to the face of the strip 28 as shown in Figure 9. In order 25 to protect the adhesive face when the device is not in use, I cover it with a removable strip of material 39. In the drawings, a lower window sash 32 is partially raised in its grooves 33 of the window frame 34, 34' and the wind shield of my invention is shown in inwardly extended position.

In order to attach my device for purposes of use, a window frame strip 28 is attached by means of its adhesive face to the upright 40 portion 35, 35' of the side window frame, that is the side portion inwardly of the room.

The two telescopic wind shield members are then positioned with respect to each 45 other to fit across the window frame, the lower edges of the shield frame members 12 and 16 placed upon the upper face of the window frame bottom 36 and the two side shields 21 and 21' are extended toward the 50 window and clasped to the window frame strips 28 and 28' by means of the male 23, 23' and the female 29, 29' clasp members. The position of the device is shown in Figure 3.

In the modified form of my device shown 55 in Figure 10, the adhesive material 37 is applied to, or carried by, the side shield 21, thus allowing the fastening of the device to the window frame without the employment of the window frame strips above described.

While I prefer to employ pliable material 60 for my side shields, I do not limit myself thereto, but the window frame strips should be of a pliable material because of the practical impossibility of adhesively attaching

a metal strip to the more, or less, uneven surface of the window frame to which it must be attached.

It will be noted from the above, that my wind shield may be attached to a window 70 frame without the use of nails, screws or other penetrating members, that the shield may be readily adapted in size and attached to any window frame, that the adhesive window frame strip may be cheaply and easily 75 replaced, if desired, and that the wind shield may be collapsed and folded into a small space for shipment or storage.

I do not limit myself to the particular size, shape, number, arrangement or material of parts as shown and described as these are given simply as a means for clearly describing the device of my invention.

What I claim is:—

1. In a wind shield, in combination, a wind 85 shield member; a side member attached to each end of the wind shield member; pliable window frame strips each having an adhesive upon the one face thereof, and means carried upon the other face of each 90 of the window frame strips and upon each of the outer faces of the side members, capable of locking the window frame strips to the side members.

2. In a wind shield, in combination, a plurality of telescopic wind shield members; a side member attached to each end of the extreme wind shield members; a plurality of locking means carried by each side member; two pliable window frame strips having an 95 adhesive upon one face thereof, and a plurality of locking means carried upon the other side thereof, capable of locking position with the side member locking means, maintaining the wind shield members in inclined position with respect to the window 100 frame.

3. In a wind shield, in combination, a plurality of telescopic wind shield members; a pliable side member attached to each end of the extreme wind shield members; a plurality of locking means carried by each side member; two pliable window frame strips having an adhesive upon one face thereof, and a plurality of locking means carried upon the other side thereof, capable of locking position with the side member locking means, maintaining the wind shield in inclined position with respect to the window 110 frame.

4. In a wind shield, in combination, a plurality of telescopic wind shield members; a triangular shaped side member attached to each end of the extreme wind shield members; a plurality of snap fastener members carried upon the outer face of each side member; two pliable window frame strips having an adhesive upon one side thereof, and a plurality of snap fastener members upon the other face thereof, capable of lock- 125 130

ing with the side member snap fasteners, maintaining the wind shield members in inclined position with respect to a window frame when the window frame strips are in adhered position upon the opposite sides of a window frame.

5. In a wind shield, in combination, a plurality of telescopic wind shield members; a triangular shaped pliable side member attached to each end of the extreme wind shield members; a plurality of snap fastener members carried upon the outer face of each side member; two pliable window frame

strips having an adhesive upon one side thereof, and a plurality of snap fastener members upon the other face thereof, capable of locking with the side member snap fasteners, maintaining the wind shield members in inclined position with respect to a window frame when the window frame strips are in adhered position upon the opposite sides of a window frame.

Signed at New York city in the county of New York and State of New York this 31st day of March, 1926.

WILLIAM H. ROSE.
